J. WHITE.

SHEET FEEDING MECHANISM.

APPLICATION FILED DEC. 7, 1916. RENEWED SEPT. 12, 1918.

1,288,780.

Patented Dec. 24, 1918.

UNITED STATES PATENT OFFICE.

JOSEPH WHITE, OF PISCATAWAY TOWNSHIP, NEW JERSEY, ASSIGNOR TO HALL PRINTING PRESS COMPANY, OF DUNELLEN, NEW JERSEY, A CORPORATION OF NEW JERSEY.

SHEET-FEEDING MECHANISM.

1,288,780.

Specification of Letters Patent. Patented Dec. 24, 1918.

Application filed December 7, 1916, Serial No. 135,591. Renewed September 12, 1918. Serial No. 253,801.

To all whom it may concern:

Be it known that I, JOSEPH WHITE, a citizen of the United States, residing at Piscataway township, State of New Jersey, (post-office address, Boundbrook, New Jersey,) have invented certain new and useful improvements in Sheet-Feeding Mechanisms; and I do declare the following to be a full, true, and exact description of said invention, such as will enable others skilled in the art to which it appertains to make use of the same.

This invention relates to mechanism for positioning sheets before they are presented to machines for operating on such sheets, and particularly to devices for positioning these sheets so that they will be printed in accurate register in printing machines.

One of the objects of the invention is to provide mechanism which will receive the head of a sheet from suitable sheet-presenting devices, and insure that the sheet will be properly squared before being presented to the front gages.

Another object of the invention is to enable sheets to be fed with very little distances between the tail of one sheet and the head of a succeeding sheet, and yet provide sufficient time in which to register the sheets.

With these and other objects in view, my invention consists of certain novel features of construction, combination and arrangement of parts as will be more fully described and pointed out in the appended claims.

In the drawings, Figure 1 represents the side elevation of an illustrative form of my invention, some of the parts being broken away;

Fig. 2 is an enlarged side elevation of a portion of the mechanism shown in Fig. 1;

Fig. 3 is a sectional elevation on the line 3-3 of Fig. 2;

Fig. 4 is a sectional elevation through a portion of the mechanism shown in Fig. 1.

The corresponding parts are referred to both in the drawings and in the specification by similar reference characters.

Referring to Fig. 1, 10 represents the cylinder of a printing machine having sheet grippers 11. 12 is a sheet feeding cylinder composed in this instance of a number of rings mounted on the shaft 13 in the usual manner. The cylinder 12 has sheet grippers 14 and rotates in unison with the cylinder 10, all in the usual manner. Below

the cylinder 12 is a series of tapes 15 passing around the rollers 16 mounted on the arms 17. These tapes are moved in any suitable manner, as is usual, and sheets to be presented to the cylinder 12 may be placed on the tapes 15 in any suitable manner, as for instance, by a sheet separating device. A series of rods 18 serve as over-guides above the sheet passing along the tapes 15 and in the same plane with the upper portion of the tapes 15 is provided a series of bars 19 which constitute a platform on which the sheet rests after it passes off the tapes 15. In the path of the sheet, passing along the bars 19 is a pair of sheet front gages 20, which may be adjustable, as is well understood and which may be of any of the well known types.

Below the bars 19 passes the upper length of a pair of chains 21 which constitute an endless carrier for one or more sheet front stops represented generally by 22, these sheet stops moving in the path of a sheet being forwarded by the tapes 15 along the bars 19. These chains 21 pass over the sprocket wheels 23-24. The sprocket wheel 24 is mounted on the shaft 25 which receives motion from the shaft 13 through a pair of intermediate gears 26-26, which engage with a gear 27 on a bushing 52 through which passes the shaft 25. The gear 27 meshes with the gear 28 connected to a gear 29, which, in turn, meshes with a gear 30 fastened to the shaft 25.

With the gearing so far described, the chains 21 would have a continuous motion, it being understood that in the illustrated embodiment of my invention, the cylinder 12 is rotating continuously. For reasons which will be pointed out later, I desire to give the chains 21 a speed which at times is less than normal, and to this end, I mount the gears 28-29 on a shaft 53, which is held in the ends of a pair of arms 31-31, pivoted on the center of the shaft 25. One of the arms 31 has an arm 32 by which the arms 31 may be oscillated through the connection 33 and the crank center 34 on the shaft 13. With the construction thus described, it will be obvious that, as the cylinder 12 rotates, the chains 21 will have a speed at times greater than, and at other times less than, the speed they would normally have if the arrangement for moving the gears 28-29 were not provided. With the cylinder 12

rotating clockwise, as shown in Fig. 1, the speed of the chains 21 will be retarded as the crank center 34 passes from the position shown in Fig. 1 to its lowermost position. Then, as it moves upward on the left hand side of the shaft 13, the chains 21 will be correspondingly accelerated in speed.

The detailed construction of my preferred form of the stops 22, which are mounted on the chains 21, is best shown in Figs. 2 and 3. The stop proper is formed by the face 35, formed at the rear of a gap composed of an upper jaw 36 and a lower jaw 37. On a projection 38, forming part of the stop 22, is mounted a pair of rollers 39 on a shaft 40. This shaft is mounted in an elongated slot and is prevented from rotating by a pin 41 which projects upwardly above the member 38 so as to contact with a flat spring 42, which tends normally to hold the shaft 40 with the rollers 39 thereon, downward.

Below the rollers 39 is mounted a pair of rollers 43. The axles 44 for these rollers are smaller than the holes in the rollers themselves, so that the rollers may have a slight motion up and down.

Extending along the side of the machine, as shown in Fig. 1, are yieldingly mounted shoes or tracks 45 normally held upward by springs 46, and limited in their upward position by the pin 47. This normal upward position is such that, as the rollers 43 are moved along from the right hand of Fig. 1 to the position shown in Fig. 1, the bottom 35 of each roller will contact with a track 45 and thus be caused to roll along it. The springs 46 serve to produce sufficient pressure to insure this rotation.

The ends of each of the axles 44 are provided with blocks 51 which engage with the under side of the bars 19 so that the centers of these axles cannot be moved upward by the pressure of the springs 46. The spring 42 serves to provide a yielding contact between the rollers 39 and 43 which will take up any variation in thickness of the sheets fed to these rollers.

Usually two of the stops 22 are provided and since these must be adjustable crosswise of the machine in order to provide for different widths of sheet, I preferably mount the tracks 45 in a member 48 which is adjustable laterally of the machine on the fixed rods 49. It will also be understood that preferably the chains 21 with the sprocket wheels 23 and 24 are also mounted for simultaneous adjustment laterally with the member 48.

Other members for bringing the sheet against the gages 20 are also illustrated, but these parts are the same, as is the preferred construction of the cylinder 12, as the corresponding parts shown in my Patent No. 1,178,563. A further description is unnecessary, since these do not form part of my present invention.

In my preferred form, I provide on the shaft 25 a roller 50 which may be covered with felt or any other suitable material, and which, by reason of its connection with the shaft 25 is made to rotate.

The operation of the preferred form illustrated is as follows:

Sheets S will be passed along the tapes 15 at a very high rate of speed. The pair of stops 22 are moving at a slower speed than the sheet and the tapes 15 tend to force the sheet against the faces 35 both to locate it and also to square it. To insure the accuracy of the squaring operation, however, I provide the rollers 39, 43. These may be separated so that the sheet passes between them and contacts with faces 35. They may also be set so that the edge of the sheet is tucked between them and prevented from reaching the faces 35 by reason of the motion derived from the tapes 15. In either case, when the tracks 45 are reached, the roller 43 and with it the roller 39 is rotated to force the edge of the sheet against the faces 35. Each set of rollers operates till the edge adjacent them is against a face 35 when the rollers slip on the sheet. This insures both sides of the front edge being placed properly against its respective stop face and the sheet being squared. Moreover, these rollers serve to hold the sheet in this squared relation.

Between the time when the sheet is received by the stops 22 until the stops 22 reach the gages 20, the rate of motion of the chains 21 is slowed down by the mechanism shown at the left of Fig. 1. Consequently, as the stops 22 reach and pass the gages 20, they are moving at a very slow speed, so that the head of the sheet is presented to the gages 20 in such a way as not to disturb the position of the sheet. Further progress of the chains 21 carries the stops 22 around the sprocket 24 from whence they will pass to the position to receive the next sheet.

The sheet having been placed against the gages 20, the final front gaging mechanism, which I have shown in Fig. 1, and which is the same as that shown in my Patent No. 1,178,563, will operate to place the sheet with absolute certainty against the gages 20. Then any suitable side gaging mechanism which may be employed will come into operation to side gage the sheet, and it will then be ready to be taken by the grippers 14 on the cylinder 12. In the arrangement I have adopted to illustrate my present invention, these grippers are arranged to lift the front of the sheet above the gages, as the head of the sheet is attached by the grippers to the cylinder 12, as described in my said Patent 1,178,563. Thereupon the head of the sheet is carried around to the position shown in Fig. 1, when it will be transferred to the fingers 11 on the cylinder 10. It will be understood that front

gages of the usual lifting type may be used if desired.

In order to provide ample time in which to bring the sheet to rest against the gages 20, and to side gage it before it is taken by the grippers 14, I have provided the roller 50 to cause the tail of the sheet to move at a faster rate than that of the head after the head of the sheet is taken by the fingers 14. It will be understood that the body of the sheet rests on the roller 50. This roller 50 being on the shaft 25, is at certain times given an accelerated motion so that it will cause the body of the sheet to travel at a faster rate than the periphery of the cylinder 12. This causes the tail of the sheet to be passed quickly over and away from the gages 20 so that the next sheet can be presented to the gages and have sufficient time in which to be side gaged before it is taken by the grippers 14. The diameter of the roller 50 is such that, when given the accelerated motion, its surface will move faster than that of the cylinder 12.

Preferably I construct the machine so that, as the tail of the sheet is fed forward at this faster rate, the body of the sheet will be permitted to buckle into a loop as shown in Fig. 1.

The embodiment of my invention may be varied within wide limits. While I prefer to use the endless carriers 21 for my front stops 22, it will be seen that many other forms of carriers may be substituted. While I have found the rollers 39-43 a very simple and efficient means for placing the head of the sheet against the front stops, it will also be understood that any other suitable mechanism may be used for the same purpose or they may be omitted entirely.

Similarly, the mechanism for giving a non-uniform rate of motion to the carriers 21 may be of any suitable construction, although I have found the construction illustrated simple and efficient.

While preferably I employ the roller 50 to move the tail of the sheet away from the gages 20, it will be understood that this function may be carried out in many different ways. For instance, particularly with some forms of sheet, it will be sufficient to have the supporting bars 19 placed at a suitable angle so that, after the head of the sheet is taken by the grippers 14 and lifted above the gages 20, there will be a tendency for the remainder of the sheet to move down by gravity at a faster rate than the head is being carried by the grippers 14. In such event, no supplemental means such as the roller 50 will be required to accelerate the speed of the tail of the sheet.

It will also be understood that if it is desired to use a roller such as 50, it may be mounted separately and rotated continuously at a suitable speed. By applying it

to the shaft 25, however, I simplify the mechanism.

It will also be obvious that the arrangement for slowing down the sheet may be used without the device for rapid moving of the tail of the sheet and vice versa.

While I have shown a cylinder 12 as a suitable carrier to take the sheets from the gages 20, it will be understood that any other form of means for taking the head of the sheet and moving it away from the gages may be used, and that after the head of the sheet is taken by such sheet-taking means, it may be presented to any form of mechanism which will operate on the sheet.

It will also be understood that the tail of the sheet may be moved quickly past the gages 20 by giving the sheet-taking means a non-uniform motion, so that the head of the sheet will be taken while such means are moving at a relatively low speed, and these means be accelerated thereafter to cause the tail of the sheet to move at a high speed.

I claim:

1. In a sheet feeding device, a front gage, means for engaging and moving the head of a sheet away from said gage, and means for accelerating the speed of the tail of the sheet after the head has been so engaged.

2. In a sheet feeding device, a sheet carrier, means thereon to attach the head of a sheet to said carrier, stationary sheet gaging means to gage the heads of sheets fed to said carrier and means to move the tail of a sheet attached to said carrier past said gaging means before the head of a succeeding sheet is presented thereto.

3. In a sheet feeding device, means to grip and carry the front edge of a sheet over a predetermined path, means to buckle the body of the sheet after the front edge is in said gripping means, to cause the body to travel over a longer path than the front edge, said gripping and carrying means and said buckling means being constructed and arranged to permit the buckle to straighten out before the front edge of the sheet is released.

4. In a sheet feeding device, means to grip and move the head of a sheet at a uniform, continuous speed over a predetermined path, accelerating means to cause the tail of the sheet to move at a greater speed than the head during a portion only of the travel of the sheet while it is under the control of said gripping and moving means, said gripping and moving means and said accelerating means being constructed and arranged to cause the tail of the sheet to travel at the same speed as the head after the speed of the tail has been accelerated and before said gripping and carrying means release the sheet.

5. In a sheet feeding device a stationary

sheet front gage, a sheet carrier, sheet grippers on said carrier arranged to engage the head of a sheet positioned against said gage to move it away from said gage at a continuous uniform speed, and means whereby the tail of the sheet is caused to move past said gage at a faster speed than the head of the sheet is moving.

6. In a sheet feeding device, a sheet carrier, means to attach the head of a sheet thereto and means moving at a greater speed than said carrier and arranged to contact and engage the tail of the sheet after the head is attached to said carrier, said carrier continuing to carry the sheet after said tail engaging means has disengaged the sheet.

7. In a sheet feeding device, a sheet carrier, means to attach the head of a sheet thereto and a bodily stationary roller constructed and arranged to engage the body of the sheet after the head is attached to said carrier and move it at a speed greater than that of the head.

8. In a sheet feeding device, an endless carrier, a front stop thereon and means traveling with the stop arranged to engage frictionally a sheet fed toward said stop and draw the front edge of the sheet against said stop.

9. In a sheet feeding device, an endless traveling belt, a pair of wheels spaced apart to support and drive said belt, a sheet front stop on said belt and means to feed a sheet toward said front stop at a higher speed and in the same direction said front stop is moving, a pair of rollers on said belt adjacent said stop and constructed and arranged to hold frictionally a sheet passed between them, and means to rotate said rollers at a predetermined point in the path of travel of said rollers to move the front edge of the sheet against said stop.

10. In a sheet feeding device, an endless carrier, a front stop thereon, sheet forwarding means to feed a sheet toward said stop and sheet feeding rollers adjacent to and moving with said stop, constructed and arranged to feed a sheet against said stop.

11. In a sheet feeding device, a moving front stop, sheet forwarding means to feed a sheet toward said stop at a speed greater than that of said stop, a pair of co-acting, normally non-rotating rollers adjacent said stop and moving therewith, each of said rollers being mounted to permit movement thereof transversely of the sheet path, means to move said rollers yieldingly transversely of the sheet path and means to rotate said rollers to feed the head of the sheet against said stop.

12. In a sheet feeding device, a moving front stop, a pair of rollers adjacent thereto and moving therewith and a yieldingly supported track adjacent the path of one of said rollers and adapted to engage it frictionally

and rotate it as said roller moves with said stop.

13. In a sheet feeding device, a non-traveling front gage, sheet forwarding means to feed a sheet toward said gage at a high speed, a moving front stop, means for supporting and moving said stop toward and past said gage in the path followed by sheets being forwarded by said sheet forwarding means, and away from said gage out of said path, said means being constructed and arranged to move the stop at a relatively high speed as it is engaged by a sheet moving toward said gage, which speed is less than that of the sheet, and at a relatively low speed as it passes said gage.

14. In combination, a rotary sheet carrier, a non-traveling front gage adjacent to said carrier, sheet forwarding means to feed a sheet toward said gage at a high speed, a moving front stop, means for supporting and moving said stop toward and past said gage in the path followed by sheets being forwarded by said forwarding means, and away from said gage out of said path, said means being constructed and arranged to move the stop at a relatively high speed as it is engaged by a sheet moving toward said gage in said path, which speed is less than that of the sheet, and at a relatively low speed as it passes said gage, and grippers on said carrier constructed and arranged to grasp a sheet positioned against said gage and carry it in the direction in which it was forwarded by said sheet forwarding means.

15. In a sheet feeding device, a front gage, a moving front stop, sheet forwarding means to feed a sheet toward said stop, means for supporting and moving said stop from sheet-receiving position up to and past said gage, said means being constructed and arranged to move the stop at a relatively high speed as it receives a sheet from said sheet forwarding means and at a relatively low speed as it passes said gage, said stop being provided with means to engage and hold the head of the sheet against it.

16. In a sheet feeding device, a front gage, sheet forwarding means to feed a sheet toward said gage at a relatively high speed, a sheet stop, an endless carrier adapted to support and move said stop in a path between said sheet forwarding means and said gage, and means to move said carrier at a non-uniform speed constructed and arranged, to cause said stop to receive the head of a sheet from said sheet forwarding means at a relatively high speed and to deposit it against said gage at a relatively low speed.

17. In a sheet feeding device, a front gage, sheet forwarding means to feed a sheet toward said gage, sheet engaging means adapted to receive the head of a sheet from

said sheet forwarding means, means to move said sheet engaging means up to and past said gage at a relatively low speed compared with the speed of said engaging means 5 when receiving the head of the sheet, said engaging means being constructed and arranged to move over the sheet after the edge thereof is against said gage.

18. In a sheet feeding device, a non-traveling front gage, frictional sheet forwarding means adapted and arranged to feed a sheet toward and against said gage at a high rate of speed, a moving front stop, means for supporting and moving said stop toward and past said gage in the path followed by sheets being forwarded by said sheet forwarding means, and away from said gage out of said path, said means being constructed and arranged to move the stop at a 15 relatively high speed as it is engaged by a sheet moving toward said gage in said path, which speed is less than that of the sheet, and at a relatively low speed as it passes said gage.

19. In combination, a rotary sheet carrier, a non-traveling front gage adjacent to said carrier, frictional sheet forwarding means to feed a sheet toward and against said gage at a high rate of speed, a moving 25 front stop, means for supporting and moving said stop toward and past said gage in the path followed by sheets being forwarded by said forwarding means, and away from said gage out of said path, said means being constructed and arranged to move the stop at a relatively high speed as it is engaged by a sheet moving toward said gage in said path, which speed is less than that of the sheet, and at a relatively low speed as it 30 passes said gage, and grippers on said carrier constructed and arranged to grasp a sheet positioned against said gage and carry

it in the direction in which it was forwarded by said sheet forwarding means.

20. In a sheet feeding device, a non-traveling front gage, a series of high speed substantially horizontal belts constructed and adapted to carry a sheet placed thereon at high speed frictionally toward and against said gage, a moving front stop, means for supporting and moving said stop toward and past said gage in the path followed by sheets being forwarded by said belts, and away from said gage out of said path, said stop passing said gage while a sheet is against 45 said stop, said means being constructed and arranged to move the stop at a relatively high speed as it is engaged by a sheet moving toward said gage in said path, which speed is less than that of the sheet, and at a 50 relatively low speed as it passes said gage.

21. In a sheet feeding device, a feed table, a non-traveling gage at one end of the feed-table, a member to receive the head of the sheets from the feed table, and the gage, 55 sheet feeding tapes for advancing a sheet frictionally at a high rate of speed over said feed board toward and against said gage, a moving front stop, means for supporting and moving said stop toward and past said 60 gage in the path of a sheet on said feed table and away from said gage out of said path, said stop passing said gage while a sheet is against said stop, said means being constructed and arranged to move the stop at a relatively high speed as it is engaged by a sheet moving toward said gage in said path, which speed is less than that of the sheet, and at a relatively low speed as it 65 passes said gage.

JOSEPH WHITE.
